UNITED STATES PATENT OFFICE.

EDMUND T. ROBY, OF DECATUR, ILLINOIS, ASSIGNOR OF ONE-HALF TO THOMAS C. BUXTON, OF DECATUR, ILLINOIS.

CARBURETER.

1,394,356.

Specification of Letters Patent.

Patented Oct. 18, 1921.

Application filed December 18, 1918. Serial No. 266,610.

To all whom it may concern:

Be it known that I, EDMUND T. ROBY, a citizen of the United States, residing at Decatur, in the county of Macon and State 5 of Illinois, have invented new and useful Improvements in Carbureters, of which the following is a specification.

One of the principal objects of my invention is to provide a novel construction of carbureter, having novel means for controlling the passage of hydrocarbon and air to the mixing-chamber.

Another object is to provide a carbureter of simplified construction, and one which is 15 compact in organization.

With these objects in view, the invention resides in the novel construction, combination and arrangement of parts of a carbureter, as hereinafter fully described in the 20 specification, pointed out in the claims, and illustrated in the drawings.

In the accompanying drawings, I have disclosed an illustratory concrete embodiment of the underlying principles of the invention. The different figures or views of the drawings may be briefly described as 25 follows:

Figure 1 is a view in top plan of my carbureter;

Fig. 2 is a view in side elevation thereof; Fig. 3 is a sectional view, on the line 3—3, Fig. 1, looking in the direction of the arrows;

Fig. 4 is a detached detail view of the stationary tubular member and of the rotatable valve-sleeve encircling the same, the sleeve being partly broken away;

Fig. 5 is a sectional view, on the line 5—5, Fig. 4.

Referring, now, in detail to the drawings:

1 designates the usual float-chamber adapted to receive and maintain a constant quantity of hydrocarbon, which may be fed thereto from an elevated tank, or by a suitable 45 pumping device, through a feed-pipe connected to a threaded, hollow coupling 2. The float-rod 3 is operatively connected, at its top, with one end of a lever 4, the other end of the latter being articulated with the 50 upper end of the needle-valve 5 controlling the flow of gasolene to the float-chamber 1. The parts so far described are well known, and form no part of my invention.

Connected with the float-chamber casing 55 is a casing 6, here shown as tubular, although

it is obvious the casing might take forms other than tubular so far as its exterior contour is concerned, the only requirement being that its interior be of tubular contour. Interiorly of this casing 6 is an internal bore of differing diameters, and, for this purpose, the casing may be provided, appropriately, with a lateral, concentric, constricted extension, or neck, 7, having an open end 8. The opposite end of the casing 65 is conveniently closed, as by a screw-cap 8^a. The extension 7 may be provided with one or more openings 9.

Disposed within the casing 6 is a tubular member 10, the end thereof adjacent the cap 70 8^a being closed, as shown at 11, and the other end thereof being open. As clearly shown in Fig. 3, the tubular member 10 projects into the extension or neck 7 and closely fits the same, so that the entire circumferential area of the portion of the member 10 within the neck 7 bears against the inner surface of the latter. The tubular member 10 is provided with an exterior circumferential flange 12, adapted to bear, preferably 80 through an interposed packing or gasket 14, against an annular shoulder 13 of the casing 6, at the inner end of the neck 7. The member 10 is appropriately provided with an opening 15 coincident with the opening 9 of 85 the neck 7.

Any suitable means may be provided for maintaining the tubular member 10 against rotation in the casing 6—in this instance, as an example, the very simple expedient of a 90 set-screw 16 is shown, which screw is screwed into the neck 7 and the member 10, as shown in Fig. 3.

It will be noticed that, by the construction described, when the tubular member 10 is in position, as shown in Fig. 3, a chamber 17 is provided between the casing 6, at the enlarged diameter thereof, and the portion of the tubular member 10 within such enlarged diameter, and this chamber constitutes the mixing chamber, as will presently appear.

The tubular member 10 is provided with a preferably rectangular opening 18 communicating with said mixing-chamber 17, 105 said opening constituting the air inlet to the mixing-chamber.

Leading from the float-chamber 1 is a port 19, passage of fluid therethrough being controlled by a manually-operable needle- 110

valve 20. Communicating with the top end of said port 19 is a pipe 21, which preferably extends across the open end of the casing 6 and thence longitudinally of and within the 5 tubular member 10, as clearly shown in Fig. 3, and terminates in a series of atomizing-holes 22 registering with similar holes in the member 10 adjacent one edge of the air-opening 18.

10 Suitable means are provided for controlling the passage of air to the mixing chamber 17 through the air-opening 18, and of the atomized fuel through the atomizing apertures 22, and, as disclosed in the drawings, I prefer to use a valve-sleeve 23 or rotary valve encircling the portion of the tubular member 10 within the larger diameter of the casing 6, said sleeve being provided with a closed end 24 and with an 20 axial stem 25 mounted in bearings 26 in the screw-cap 8^a. The exteriorly projecting end of the stem 25 is articulated with a crank 27 operatively connected, through intermediate mechanism (not shown) with some control member (such, for instance, as the steering-wheel lever) within convenient reach of the operator of the automobile equipped with my carburetor; or such valve may be automatically controlled by a governor in 30 accordance with the speed of the engine.

The valve-sleeve 23 is provided with an opening 28, which, in contradistinction to the air-opening 18 in the tubular member 10, is not rectangular, but has an oblique 35 or slanted side or edge 28^a,—*i. e.*, a side or edge which is formed at an angle to the longitudinal plane in which the other side or edge 28^b is formed. The opening 28 is arranged relative to the opening 18 so that, 40 when the valve-sleeve 23 is partially rotated from the position thereof shown in Fig. 4, the oblique side 28^a of the opening will gradually sweep over the air-opening 18 and will then sweep over the atomizing apertures 22 successively. A stop 29, in this instance a screw, carried by the tubular member 10, is adapted to engage a recess 30 in the sleeve-valve 23, to limit movement of the valve-sleeve in one direction of rotation, 45 and the same stop contacting with the oblique edge 28^a of the opening 28 limits movement of the valve-sleeve in the opposite direction of rotation; but, manifestly, any other desired arrangement may be provided 50 for limiting rotary movement of the sleeve-valve.

Carried exteriorly of the sleeve-valve 23 is a screen 31, of fine mesh, which breaks up the gasolene passing to the mixing-chamber 17 and causes an intimate admixture of the air with the gasolene; *i. e.*, the screen acts as a strainer to finely divide the air and permit it to absorb a greater quantity of gasolene, to form proper vapor.

65 If desired, an auxiliary, automatically-

operable air-valve, 32 may be provided, said valve communicating with the mixing-chamber 17.

The operation is thought to be apparent from the foregoing detailed description of the construction and structural combination; but, briefly stated, it is as follows: Gasolene passes from the float-chamber 1 and, through the port 19, thence through the pipe 21 and by suction, through the atomizing-holes 22, and into the mixing-chamber 17, with the valve 23 in the position shown in Fig. 4, in which position the valve-opening 28 uncovers the atomizing-apertures 22, as shown. Air passes through the tubular member 10, entering at the open end thereof, and through the coincident apertures 9 and 15, and escapes through the air-exit 18 in the tubular member into the mixing-chamber 17, the air and gasolene also passing through the screen 31, and being thoroughly commingled, and the air vaporized. Thence, the fuel mixture passes through the throttle-valve chamber 33 to the engine. Regulable quantities of air and gasolene passing to the mixing-chamber may be obtained by rotation of the valve-sleeve 23.

In compliance with the patent statutes, I have described with great particularity one form of embodiment of my invention; but it is to be recognized that changes may be made in the physical embodiment, within the terms of the appended claims, without departing from the spirit of the invention.

Having thus fully described my invention, 100 what I claim as new and desire to secure by Letters-Patent is:

1. In a carburetor, the combination, with a tubular casing open, at one end, for the admission of air, of a tubular member disposed within, and having an open end coincident with the open end of, said casing, said casing and member being arranged to provide therebetween a mixing-chamber, said member being provided with an air-aperture communicating with said mixing-chamber, and with a series of atomizing-perforations adjacent said air-aperture, a gasolene-conveying pipe entering said casing and communicating with said perforations, and a rotary valve revolvably mounted on said member and controlling passage to said mixing-chamber, through said air-opening and atomizing-perforations, of the air and gasolene.

2. In a carburetor, the combination, with a tubular casing open, at one end, for the admission of air and closed at the other end, a tubular member disposed within, and having an open end coincident with the open end of, said casing, said casing being provided with an internal shoulder and said tubular member with a circumferential flange bearing against said shoulder, the portions of said casing and member lying between the

- closed end of said casing and said flange providing therebetween a mixing-chamber, said member being provided with an air-aperture communicating with said mixing-chamber, and with a series of atomizing-perforations adjacent said air-aperture, a gasoline-conveying pipe entering said casing and communicating with said perforations, and a rotary valve revolvably mounted on 5 said member and controlling passage to said mixing-chamber, through said air-opening and atomizing-perforations, of the air and gasoline.
3. In a carbureter, the combination of a 15 casing; a second casing of smaller diameter nested in said first casing to provide a mixing chamber between said casings, said smaller casing having an air inlet and an air outlet delivering to said mixing chamber; gasoline feeding means delivering adjacent the air outlet of said inner casing; and a sleeve valve revolvably mounted on said inner casing and controlling both the air outlet and gasoline feed to the mixing chamber.
4. In a carbureter, the combination of a 20 casing; a tubular casing of smaller diameter nested in said first casing to provide a mixing chamber between said casings, said smaller casing being open at one end and having an air outlet in its side wall delivering to said mixing chamber; gasoline feeding means delivering through the wall of said inner casing adjacent the air outlet; a sleeve 25 valve revolvably mounted on said inner casing and controlling both the air outlet and gasoline feed to the mixing chamber; and means for operating said valve exteriorly of said casing.
5. In a carbureter, the combination of a 40 casing; an open ended tubular casing of smaller diameter, nested in said first named casing and having an air outlet in its wall delivering to the mixing chamber between the two casings; gasoline feeding means traversing said open ended inner casing and delivering through the side wall thereof adjacent said air outlet; and a sleeve valve revolvably mounted on said inner casing and controlling both the air outlet and the gasoline feed to the mixing chamber.
6. In a carbureter, the combination of a 45 casing having a removable cap at one end; an open ended casing of smaller diameter nested in said first casing, and having an air outlet in its side wall delivering to the mixing chamber between the two casings; gasoline feeding means traversing said open ended inner casing and delivering adjacent the air outlet to the mixing chamber; an 50 open ended sleeve valve revolvably seated on said inner casing, and having a port controlling both the air outlet and gasoline feed; and a valve operating spindle mounted in and projecting through the said closing 55 cap for said outlet casing.
- In testimony whereof I have hereunto set my hand.
- EDMUND T. ROBY.
